UNITED STATES PATENT OFFICE.

WILLIAM H. WRIGHT, OF INDIANAPOLIS, INDIANA.

FLUID-STREAM-PRESSURE GOVERNOR.

1,305,762.

Specification of Letters Patent. Patented June 3, 1919.

Application filed May 9, 1917. Serial No. 167,623.

To all whom it may concern:

Be it known that I, WILLIAM H. WRIGHT, a citizen of the United States, residing at Indianapolis, in the county of Marion and 5 State of Indiana, have invented a new and useful Fluid-Stream-Pressure Governor, of which the following is a specification.

It is the object of my invention to provide a simple pressure governor for maintaining 10 a substantially constant pressure, whether above or below atmospheric pressure, in a fluid stream.

I do this by controlling a bleeding opening whereby fluid may be admitted to or 15 allowed to escape from the main fluid stream to maintain the desired pressure in such stream; and I control this bleeding opening by a balanced valve operated by a governing gas holder which is connected to the fluid 20 stream so that the gas holder movements are effected by changes in the pressure in the fluid stream, the gas holder being acted on in one direction by a constant force so that its movement in either direction continues until 25 the bleeding to or from the fluid stream changes the pressure in such stream so that it returns to the normal determined by such constant force. I guide the movements of the gas holder and balanced valve by a lever 30 provided with arc-shaped segments at the ends and connected by flexible members to the moving parts, so that constant lever arms are obtained and there is a minimum of friction; and I prefer to obtain the 35 constant force by a weight. The bleeding opening may be and ordinarily is direct to or from the atmosphere.

My invention is especially adapted for controlling the pressure condition within a 40 flue from a furnace, and more particularly within the flue from a coke oven, and is also well adapted for the control of the pressure of the fluid stream discharged from a blower.

45 The accompanying drawings illustrate my invention. Figure 1 is a diagrammatic view showing my invention applied to the flue from a coke oven; and Fig. 2 is a similar diagrammatic view showing my invention applied to a pipe carrying gaseous fluid under pressure.

In Fig. 1, the flue 10 from a coke oven is shown as discharging into the base of a stack 11. It is necessary to maintain the draft substantially constant through the flue 10, by 50 maintaining a substantially constant pressure

condition therein, in order to secure a satisfactory operation of the coke ovens. To this end, I provide near the base of the stack 11 a lateral pipe 12 communicating with the 60 stack and provided with air-admitting openings 13 controlled by a balanced valve 14. The two valve disks of this valve are preferably slightly smaller than said openings and are mounted on a stem 15 which is connected to the bell 16 of a gas holder 17, containing liquid into which said bell 16 dips, the space beneath the bell but above the liquid being connected by a pipe 18 to the 70 flue 10 at the point where it is desired to maintain a constant pressure condition. In this case, this pressure condition is less than atmospheric pressure. The pressure condition beneath the bell 16 is the same as that in the flue 10. The rod 15 is also connected by 75 a flexible member 19 to an arc-shaped segment 20 at one end of a suitably supported lever 21, on the other end of which there is a segment 22 to which is connected another flexible member 23 from which is hung a 80 weight 24.

The weight 24 tends to lift the rod 15 and move the valve disks 14 toward closed position. This tendency is opposed by the difference between the actions of atmospheric 85 pressure and the flue pressure on the bell 16, which difference in pressure tends to move the rod 15 downward and the valve disks 14 to a more open position. The disks 14 of the balanced valve when not fully 90 closed—and the system is designed so that they are practically never fully closed—admit air from the atmosphere into the base of the stack 11, thus diminishing the draft 95 created in the flue 10 and cutting down the partial vacuum in such flue from what it would otherwise be. The valve disks 14 take a position of equilibrium, determined by the opposing actions of the weight 24 and the differential pressure on the bell 16. When 100 the draft in the flue decreases so that the pressure rises (or the partial vacuum decreases) in the flue 10, this equilibrium is disturbed and the weight 24 overpowers the differential pressure on the bell 16 so that 105 the valve disks 14 are moved toward closed position. This reduces the amount of air bled into the base of the stack 11, thereby decreasing the pressure (or increasing the partial vacuum) in the flue 10, which tends 110 to restore the lost equilibrium. The movement of the valve disks 14 continues until

the equilibrium is restored. When the draft in the flue increases so that the pressure falls (or the partial vacuum increases) in the flue 10, such equilibrium is disturbed in the other 5 direction and the excess of the differential pressure on the bell 16 overpowers the weight 24 and moves the valve disks 14 farther open, thus admitting more air to decrease the draft in the flue 10 and increase 10 the pressure (or decrease the vacuum) therein until the lost equilibrium is again restored. By this means, a substantially constant pressure condition in the flue 10 is maintained, within very close limits, the 15 movements of the balanced valve and associated parts being sufficiently quick upon slight changes in the pressure in the flue to prevent such changes from becoming unduly large.

20 The arrangement shown in Fig. 2 illustrates the application of my invention to a pipe carrying a gaseous stream under pressure greater than atmospheric pressure, whereas the arrangement shown in Fig. 1, 25 illustrated the invention as applied to a stream in which the pressure is less than atmospheric pressure. In the arrangement of Fig. 2, the pipe 30 carries a gaseous stream from any suitable source, such as air from a 30 blower, the stream flow being in the direction of the arrows. The pipe 30 is provided with air outlet openings 33 governed by a balanced valve 34 the disks of which are mounted on a rod 35. The rod 35 of this 35 balanced valve is suitably connected, as is the balanced valve of Fig. 1, to the bell 16 of the gas holder 17, the space beneath the bell communicating by the pipe 18 with the pipe 30 at the point where the constant pressure is desired. Here, however, the rise of 40 the bell 16 tends to open the balanced valve, whereas in the arrangement shown in Fig. 1 such rise tends to close such balanced valve, because in the arrangement shown in Fig. 2 45 the desired pressure is greater than atmospheric. I prefer to connect the rod 35 and the bell 16 in the arrangement shown in Fig. 2 through the lever 21 with its segments 20 and 22 and the coöperating flexible members 50 19 and 23, a suitable weight 24 being placed on the bell 16 if necessary in order to obtain the desired pressure condition. In effect, the arrangement shown in Fig. 2 differs from that shown in Fig. 1 in that the gas holder 55 is transferred to the other end of the lever 21, so that it acts directly on the weight 24 instead of directly on the rod 15.

In operation, the balanced valve 34 is moved toward or from closed position to 60 vary the leakage from the pipe 30 to the atmosphere and thus to maintain a substantially constant pressure at that point in the pipe 30 to which the pipe 18 is connected. Upon an increase in the pressure at this 65 point, the bell 16 is lifted to open the valve

disks 34 and permit a greater leakage from the pipe 30, thereby returning the pressure to normal. Upon a decrease in the pressure in the pipe 30 the reverse action occurs. In either movement of the valve disks 34, the movement continues until the lost equilibrium between the forces acting on the lever 21 is restored, which occurs when the desired pressure condition is reached.

I claim as my invention:

1. In combination, a conduit carrying a fluid stream and provided with a bleed opening communicating therewith, a balanced valve controlling said bleed opening, a gas holder the bell of which is connected to said balanced valve to operate it, the space beneath the bell of said gas holder being connected with said conduit, and means whereby the forces acting on such bell are substantially constant save for the variations in pressure beneath it.

2. In combination, a conduit carrying a fluid stream and provided with a bleed opening communicating therewith, a balanced valve controlling said bleed opening, a gas holder having a bell the space beneath which is connected with said conduit, said bell being connected to said balanced valve to operate it, and means whereby said valve is acted on by forces which are substantially constant save for the variations in pressure beneath the bell, said means including a lever provided at its ends with arc-shaped segments over which pass flexible members one of which is connected to said balanced valve.

3. In combination, a flue communicating with a stack, the conduit formed by said flue and stack being provided with a bleed opening from the atmosphere for admitting air to such conduit, a balanced valve controlling such bleed opening, a gas holder the bell of which is connected to said balanced valve so that when the bell rises and falls the balanced valve is moved toward and from closed position respectively, the space beneath such bell being connected to such conduit, and means whereby the forces acting on such bell and valve are substantially constant save for variations in pressure beneath such bell.

4. In combination, a flue communicating with a stack, the conduit formed by said flue and stack being provided with a bleed opening from the atmosphere for admitting air to such conduit, a balanced valve controlling such bleed opening, a gas holder the bell of which is connected to said balanced valve so that when the bell rises and falls the balanced valve is moved toward and from closed position respectively, the space beneath such bell being connected to such conduit, and means whereby the forces acting on such bell and valve are substantially constant save for variations in pressure beneath such bell.

such bell, said means including a lever provided at its ends with arc-shaped segments over which pass flexible members one of which is connected to said valve and the other to a weight.

5. In combination, a conduit carrying a fluid stream and provided with two oppositely disposed bleed openings communicating therewith, a balanced valve comprising two rigidly connected plates coöperating with said respective bleed openings so that when one plate moves inwardly the other moves outwardly, said plates being slightly smaller than the openings with which they 10 coöperate so that they clear the edges thereof, and means controlled by a condition of the fluid in the stream for controlling said balanced valve.

6. In combination, a conduit carrying a fluid stream and provided with a bleed opening communicating therewith, a balanced valve controlling said bleed opening, and a gas holder the bell of which is connected to said balanced valve to operate it, the space 20 beneath the bell of said gas holder being connected with said conduit, and said bell and balanced valve being arranged so that the forces acting thereon include but one variable which is the pressure beneath such bell 25 and are in equilibrium when the desired

pressure condition in the fluid stream exists and tend to move the valve in a direction to restore such equilibrium when it is destroyed by a change from such desired pressure.

7. In combination, a flue communicating with a stack, the conduit formed by said flue and stack being provided with a bleed opening from the atmosphere for admitting air to such conduit, a balanced valve controlling said bleed opening, and a gas holder the bell of which is connected to said balanced valve so that when the bell rises and falls the balanced valve is moved toward and from closed position respectively, the space beneath such bell being connected with said conduit, and said bell and balanced valve being arranged so that the forces acting thereon include but one variable which is the pressure beneath such bell and are in equilibrium when the desired pressure condition within such conduit exists and tend to move the valve in a direction to restore such equilibrium when it is destroyed by a change from such desired pressure.

In witness whereof I have hereunto set my hand at Indianapolis, Indiana, this seventh day of May, A. D. one thousand nine hundred and seventeen.

WILLIAM H. WRIGHT.
